(57) **CLAIM**

The ornamental design for a distal cap for a working channel tube, as shown and described.

DESCRIPTION

FIG. 1 is a perspective view of a distal cap for a working channel tube of the present invention;

FIG. 2 is a top plan view thereof;

FIG. 3 is a front view thereof;

FIG. 4 is a bottom view thereof;

FIG. 5 is a rear view thereof;

FIG. 6 is a left side view thereof; and,

FIG. 7 is a right side view thereof.

The dash-dot-dot lines showing the hose in the figure drawings are included to show unclaimed portions only and form no part of the claimed design.
